UNITED STATES PATENT OFFICE.

EMIL C. STAUDINGER, OF NEW ORLEANS, LOUISIANA.

STOPPER FOR RECEPTACLES.

SPECIFICATION forming part of Letters Patent No. 769,775, dated September 13, 1904.

Application filed May 23, 1904. Serial No. 209,283. (No model.)

To all whom it may concern:

Be it known that I, EMIL C. STAUDINGER, a citizen of the United States of America, residing at New Orleans, in the parish of Orleans 5 and State of Louisiana, have invented certain new and useful Improvements in Stoppers for Receptacles, of which the following is a specification.

This invention relates to packing and storing vessels, and particularly to a class thereunder known as "stoppers."

An object of this invention is to provide novel means for effecting the closing of a spout of a receptacle in order to prevent the entrance of fire to the receptacle and also to prevent the evaporation of the contents of the said receptacle.

Furthermore, an object of the invention is to provide novel means for withdrawing the 20 stopper from the spout with the elevation of the receptacle by the hand of an operator and the provision of means for permitting proper movement of the stopper independently of its carrying member when it is withdrawn from 25 the spout.

Finally, an object of the invention is to produce a stopper and closing means which will prove efficient and satisfactory in use, strong and durable, and comparatively inexpensive 30 to manufacture.

With the foregoing and other objects in view the invention consists in the details of construction and in the arrangement and combination of parts to be hereinafter more fully 35 set forth and specifically claimed.

In describing the invention in detail reference will be had to the accompanying drawings, forming part of this specification, wherein like characters denote corresponding parts 40 throughout the several views, in which—

Figure 1 is a view in perspective of a receptacle, its stopper, and the operating means embodying the invention. Fig. 2 is a similar view showing the stopper seated to close the 45 spout.

In the drawings, A indicates the receptacle, which may be metallic or wooden, and B is a spout which may be of any ordinary construction and which may be located at any convenient position on the head of the receptacle.

The upper surface of the head of the receptacle is provided with ears C, having apertures c for the reception of the pintles D of the arm d, the said arm d being rocked with relation to the spout B, as occasion requires. Transversely of the arm d is a short rod E, which is secured to the said arm in any convenient way, and the said rod affords means for engaging the fingers or hand of an operator for supporting the receptacle when in the act of pouring the contents of the receptacle through the spout. A spring F may be constructed in different ways, and I do not, therefore, wish to be confined to any particular shape; but I here show for the purpose of disclosing an operative device a spring comprising a wire which is bent on itself to form a loop at the point f, where it is anchored to the top of the receptacle by solder, or it may be secured by a clip or in any other suitable manner. The metal from which the spring is formed has its portions diverging slightly and wound around the pintle D and having its ends extending upwardly into engagement with the arm d, to which the said ends are secured by brazing or 75 in any suitable manner, or, if desired, the ends need not be secured to the arm, but may by resting on the upper surface of the bar E have sufficient anchorage to prevent their dislodgement and to cause their operation in the proper 80 way. As a matter of fact the portions of the spring need not be wound around the pintle, and the two portions of the spring which are divided may consist of two separate pieces.

On the outer end of the arm d is carried a stopper G, which has its lower end tapered to a point, and intermediately the length of the said stopper is an annular flange g, of rubber or other yielding material, which arrests the downward movement of the said stopper by 90 reason of its engagement with the wall of the spout, and the said engagement also effects the sealing of the spout and serves to prevent evaporation of the contents of the receptacle. This stopper G is composed of any suitable 95 material; but it is preferable that the said stopper be weighted or have a weight greater than that of wood in order that it will gravitate readily and seal the spout when the arm d is released; but it is my purpose to have the spring 100

F assist in causing the stopper to enter the spout, and it is also my purpose to have the spring retain the stopper in place in case the receptacle is tilted or upset. The stem H is 5 pivoted to the stopper in order that the said stopper may have free movement, and the said stem has a bifurcation h in its end, in which the end of the arm d is pivoted by means of the pin h'. A guide-rod I has one end anchored in the lower end of the stopper, and the said guide-rod depends into the receptacle at 10 all times, but is partially withdrawn with the withdrawal of the stopper. The end which is not withdrawn is caused to engage the wall 15 of the opening of the spout, and as the said arm and stopper descend the guide-rod serves to cause the stopper to travel in such relation to the spout as to insure the said stopper being seated to seal the opening of the spout. 20 The stopper is secured on the stem by means of the pin J, (shown in dotted lines in Fig. 2,) which passes through the piece j of the stopper and through the said stem.

A handle K is attached, preferably near the 25 bottom of the receptacle, to be used when the operator desires to pour the contents of the receptacle.

In operation the bar E is grasped and the arm d is swung on its pivot until it stands approximately vertical, and in which position the stopper is removed from the spout, as shown in Fig. 1, and then by grasping the handle K the receptacle may be tilted to any desired angle and manipulated. When the 35 receptacle is again brought to stand upright or to an upright position and the arm d is released, the weight of the stopper, augmented by the action of the spring, causes the seating of the stopper and the sealing of the spout.

40 Having fully described the invention, what I claim as new, and desire to secure by Letters Patent, is—

1. In combination with a receptacle having

a spout, an arm pivoted with relation to the receptacle, a weighted stopper carried by the 45 said arm and a guide depending from the stopper into the receptacle through the spout, substantially as described.

2. In combination with a receptacle having a spout, an arm pivoted with relation to the 50 spout, a weighted stopper carried by the arm, a guide depending from the stopper into the receptacle through the spout, and a spring exerting pressure to hold the arm normally depressed. 55

3. In combination with a receptacle having a spout, an arm pivoted with relation to the spout, a rod secured transversely of the arm, a spring for holding the arm normally depressed and a weighted stopper pivoted to the 60 arm, substantially as described.

4. In combination with a receptacle having a spout, an arm pivoted with relation to the spout, a rod secured transversely of the arm, a spring for holding the arm normally depressed, a weighted stopper pivoted to the 65 arm, and a guide-rod depending from the inner end of the stopper into the receptacle through the spout, substantially as described.

5. In combination with a receptacle having a spout, an arm pivoted to the receptacle in certain relation to the spout, a stopper carried by the arm, a weight provided for the stopper, a depending rod carried by the stopper, extending into the receptacle through the 75 spout, a spring anchored to the top of the receptacle and extending around the top of the arm and exerting a pressure on said arm, substantially as described. 70

In testimony whereof I affix my signature, in 80 the presence of two witnesses, this 19th day of May, 1904.

EMIL C. STAUDINGER.
